US00D961997S

(12) **United States Design Patent** (10) **Patent No.:** **US D961,997 S**
(45) **Date of Patent:** **** Aug. 30, 2022**

(54) **FLASK**

(71) Applicant: **Natura Cosméticos S.A.**, São Paulo (BR)

(72) Inventors: **Márcio Miranda de Faria**, Cajamar (BR); **Thiago Milano de Oliveira**, Cajamar (BR); **Gideon Moreira Ferreira**, Cajamar (BR); **Josué Ferreira**, São Paulo (BR)

(73) Assignee: **NATURA COSMÉTICOS S.A.**, São Paulo (BR)

(**) Term: **15 Years**

(21) Appl. No.: **29/820,381**

(22) Filed: **Dec. 21, 2021**

Related U.S. Application Data

(62) Division of application No. 29/722,913, filed on Feb. 3, 2020, now Pat. No. Des. 943,351.

(57) **CLAIM**

We claim the ornamental design for a flask, as shown and described.

DESCRIPTION

FIG. 1 is a top perspective view of a flask showing our new design;

FIG. 2 is an exploded view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dash broken lines in FIG. 2 illustrate portions of the flask that form no part of the claimed design. The dash-dash broken lines in FIG. 8 represent bounds of the claimed design and form no part of the claimed design, and the portions of the flask shown therein form no part of the claimed design.
